UNITED STATES PATENT OFFICE.

ADA COWAN KENDRICK, OF WILLIAMSBURG, KANSAS.

TYPE-WRITER ATTACHMENT.

939,265.

Specification of Letters Patent. Patented Nov. 9, 1909.

Application filed July 17, 1908. Serial No. 538,120.

To all whom it may concern:

Be it known that I, ADA COWAN KENDRICK, a citizen of the United States, residing at Williamsburg, in the county of Franklin and State of Kansas, have invented a new and useful Type-Writer Attachment, of which the following is a specification.

This invention has reference to improvements in typewriter attachments and is designed more particularly as an attachment to be applied to typewriters for operating the shift key which latter in the standard or universal keyboard is at the left-hand end of the lower line of key levers.

The present invention is an improvement over the structure shown and described in an application Serial No. 469,759 filed by me on December 29, 1908, for improvements in typewriters. In the structure shown in the said application the shift key is actuated by a lever extending across the keyboard back of the space bar and provided with a manipulating member intermediate of the width of the keyboard, but this structure is such as would necessitate the employment of skilled labor to secure the device in place. With the present invention this is avoided since no change whatsoever is required in the frame of the machine and the attachment may be applied by any user of the machine although unskilled in the use of tools. Furthermore, the present attachment may be made cheaper than the one shown and described in the aforesaid application.

The invention will be best understood from a consideration of the following detail description taken in connection with the accompanying drawings forming a part of this specification, in which drawings,

Figure 1 is a plan view of so much of a typewriter keyboard as is necessary for the understanding of the present invention, with the attachment applied. Fig. 2 is a perspective view of the attachment unassociated with the keyboard.

Referring to the drawings there is shown a portion of a typewriter frame 1 with the lower range of keys 2 of a keyboard of the standard or universal type, and this showing may be taken as typical of any one of a number of commercial forms of typewriters.

The attachment forming the subject matter of the present invention is best shown in Fig. 2 where it will be seen that there is provided a U-shaped clip 3, the clip being used

with the connecting member of the U uppermost and is designed to fit over the front member of the frame 1 with the side members of the U extending downward on each side of the front member of the frame 1.

At the central portion of the clip 3 are formed downwardly extending wings 4 from both legs of the U and these wings are suitably perforated for the passage of a bolt 5 by means of which the clip may be secured to the frame, the wings 4 extending below the lower edge of the front member of the frame 1 and being there joined by the bolt 5 which passes through the wings below the frame. 70

The lower edge of one leg of the clip 3, this leg being the front leg when the attachment is in position on the typewriter, is formed into two elongated journal bearings 6 by bending the metal of which the clip is 75 made into cylindrical form, and through these two journal bearings 6 there extends a shaft 7 in the form of a rod having one end 8 bent at right angles to the length of the shaft 7 and then curved away from the front of the clip toward the rear thereof until, when the attachment is on a machine, this portion of the member 8 is immediately over the space bar of the typewriter machine, which space bar is indicated in the drawings 80 at 9. The free end of the member 8 is then bent in a position parallel with relation to the space bar 9 as indicated at 10 and this portion 10 carries a covering 11 which may be of cylindrical shape or any other suitable 85 shape and is designed to be engaged by the thumb of the operator. The other end of the shaft 7 is curved so as to under-ride the frame 1, this curved portion being indicated at 12, and from thence the shaft or bar is 90 continued in a direction to lie alongside of the shift key at the left-hand end of the keyboard, this shift key being indicated at 13, and the portion of the rod or shaft lying alongside of this shift key is indicated at 14. 95 The free end of the portion 14 is bent into the form of a hook 15 so as to over-ride and partially embrace the lever member of the shift key 13.

When the attachment is in place then the 105 manipulating end of the shaft 7, which end is indicated at 11, is located approximately midway of the length of the keyboard and substantially immediately over the center of the spacing bar. In this position of the 110 parts the hook end of the extension 14 engages over the shift key lever at a point

near the free end of the lever and the parts are so proportioned that the operator on depressing the manipulating end 11 of the shaft 7 will move the same through a distance about the distance necessary to move the shift key when directly engaged by the finger of the operator.

The attachment may be very cheaply constructed since the clip 3 may be stamped out 10 of sheet metal and the parts thereof bent into the desired shape, while the shaft 7 and its continuation may be made out of heavy wire or a round bar of suitable gage while the manipulating portion 11 may be molded 15 out of rubber or celluloid or like material.

The general advantages of this invention have been fully set forth in the aforesaid application, but it may be stated herein that with keyboards of the type shown in the 20 drawings it is customary to move the shift key with the little finger of the operator's hand and since the entire carriage of the typewriter must be moved by means of this shift key a greater task is imposed upon the 25 weakest finger of the hand than upon any of the other and stronger fingers.

By means of the present invention the strongest member of the hand, namely the thumb, may be employed to cause the shifting 30 of the carriage, and because of the central location of the shift key extension forming the subject matter of the present invention, the shifting of the carriage may be readily brought about by the use of the 35 thumb of either hand of the operator at will.

It will be observed that the attachment is adaptable to different commercial forms of typewriters, in some without any modifications whatsoever of the structure shown in 40 the drawings and to others with some slight modifications of the shape or length of the parts, the structure remaining substantially the same in all instances. It will also be observed that the longitudinal axis of the 45 shaft 7 is parallel with the length of the spacing bar and at right angles to the length of the shift key. Furthermore, the manipulating end 8 of the shaft and the shift key engaging end 14 thereof extend from 50 the shaft in the same direction and while there is some increase of leverage, the movement of the manipulating end 11 is but little more than the key end 13 of the shift key.

What is claimed is:—

1. An attachment for typewriters comprising a clip adapted to engage and be secured to the frame of a typewriting machine, and a shaft journaled in the clip and having one end bent to over-ride the space bar of the machine and the other end bent to engage the shift key lever of the machine.

2. An attachment for typewriters comprising a sheet metal clip adapted to engage and be secured to the frame of a typewriting machine and having an aligned portion bent into journal bearings, and a shaft journaled in the bearings formed on the clip and having one end bent to over-ride the space bar of the machine and the other end bent to engage the shift key lever of the machine.

3. An attachment for typewriters comprising a sheet metal clip of U shape having centrally located wings extending from the free edges of the legs of the clip and having portions of the edge of one leg bent into cylindrical form to constitute journal bearings, and a shaft extending through the journal bearing formed on the clip and having one end bent to over-ride the space bar of the machine when the clip is attached and the other end bent to engage the shift key lever of the machine.

4. An attachment for typewriters comprising a clip adapted to engage and be secured to the frame of a typewriting machine and provided on one side with bearings, and a shaft journaled in said bearings and movable about an axis parallel with the length of the clip, said shaft having its ends bent in the same general direction, one end terminating in a manipulating handle adapted to over-ride the space bar of the machine when the clip is applied and the other end being bent to under-ride the frame of the machine and to extend along the shift key lever at the corresponding end of the machine and terminating in a hook portion adapted to engage over said lever.

In testimony that I claim the foregoing as my own, I have hereto affixed my signature in the presence of two witnesses.

ADA COWAN KENDRICK.
